No. 888,531.

PATENTED MAY 26, 1908.

J. A. RAITH.

HINGE.

APPLICATION FILED MAR. 18, 1907.

UNITED STATES PATENT OFFICE.

JULIUS A. RAITH, OF PHILADELPHIA, PENNSYLVANIA.

HINGE.

No. 888,531.

Specification of Letters Patent.

Patented May 26, 1908.

Application filed March 18, 1907. Serial No. 362,795.

To all whom it may concern:

Be it known that I, JULIUS A. RAITH, a citizen of the United States, residing at the city of Philadelphia, in the county of Philadelphia and State of Pennsylvania, have invented a certain new and useful Hinge, of which the following is a specification.

This invention relates to hinges, and while being applicable to various objects designed 10 to be hinged, it is particularly adapted for bar fixtures.

It is customary to have attached to the rear of the bar of a saloon a housing or chest adapted to contain the necessary accessories 15 suitable for such a business. This housing is provided with a lid that is hinged to the bar and it is desirable that the hinge or hinges shall not project above the level of the bar and lid top. As the bar is usually a highly 20 polished and expensive piece of wood, it is desirable that the same shall not be marred by countersinking the same for the reception of hinges.

The principal object of the present invention 25 is to provide a neat, simple, and comparatively inexpensive hinge that shall lie flush with the hinged parts, and which may be applied without countersinking the same, and which will offer no obstructing parts.

30 A further object of the invention is to provide a hinge of the above character having a spacer or separator against which the flaps of the hinge abut when in normal position to prevent sagging of the hinged part.

35 The invention consists of the improvements hereinafter described and finally claimed.

The nature, characteristic features and scope of the invention will be more fully 40 understood from the following description taken in connection with the accompanying drawings forming part hereof and in which:

Figure 1 is a perspective view of a hinge, in open position embodying the invention. 45 Fig. 2 is a sectional view of the same in closed or normal position. Fig. 3 is a top or plan view of the same. Fig. 4 is a perspective view showing the application of the hinge to a bar and its complemental rear housing, and Fig. 5 is a sectional view of a 50 portion of Fig. 4.

In the drawings, the hinge is shown as comprising a pair of independent leaves *a*, whereof one of said leaves is adapted to be fixed and 55 the other movable, arranged in parallelism. The outer faces *b*, of these leaves are flat and

the inner faces *c*, are provided with a plurality of inwardly extended and oppositely disposed knuckles *d*, having pintle openings *e*, therethrough. These leaves are cut away 60 intermediate of the knuckles to form an opening *f*. Interposed between the leaves and accommodated within the opening *f*, is a connecting link *g*, having pintle openings 65 therethrough that register with the pintle openings of the leaves *a*, and are adapted for the reception of the pintles *h*. This connecting link has a flat outer surface *i*, that is adapted to come flush with the outer parts 70 of the hinge when in normal position, that is, when the part to be hinged is in closed position. This link is also provided with an inwardly extended lug *g'*, comprising a spacer or separator against which the inner faces of the leaves abut when in normal position 75 to prevent sagging of the hinged or movable part. Obviously such a hinge is adapted to be used for numerous purposes, but it is particularly adapted for bar fixtures, and in Figs. 4 and 5 of the drawing, its application thereto is illustrated. In said figures the bar *k*, is shown as being provided at the rear thereof with the usual housing *l*, having thereon a lid *m*. The flat faces of the leaves fit against and are screwed fast to the meeting edge of the bar and lid thus obviating the necessity of marring the top of the bar, which is usually a highly polished and expensive piece of fixture. By referring to Fig. 5, it will be observed that the upper or exposed 80 part of the knuckles, link, bar, and lid are all in the same plane and no obstructions of any character are present. This is important in the dispensing of liquid refreshment over the bar for the reason that if obstructions are 85 present, the glasses used in the business are apt to become nicked by continual coming in contact therewith or else the contents thereof are partially spilled. The spacer or separator is likewise important in this respect in 90 that it serves to prevent sagging of the lid and keeps the top of the same upon a level with the top of the bar.

I do not intend by the use of the above language to limit the invention further than the prior state of the art may require; but

Having thus described the nature and objects of the present invention what I claim as new and desire to secure by Letters Patent is:—

The combination in a fixed and movable element of a hinge for hinging said movable

element to the fixed element, said hinge comprising a pair of vertically arranged leaves having flat outer faces of which one of said faces is secured to the inner edge of said fixed element, and the flat face of the other leaf is applied to the countersunk portion of the said movable element, the said leaves being provided with inwardly extended, oppositely disposed, curved knuckles having pintle passages therethrough, the portion of the leaves between said knuckles being cut away for the reception of a connecting link having a

spacer and also having curved knuckles provided with pintle passages therethrough adapted to register with the aforesaid pintle passages and pintles for securing the leaves and link. 15

In testimony whereof, I have hereunto set my hand in the presence of

JULIUS A. RAITH.
